UNITED STATES PATENT OFFICE.

GEORGE W. BLAIR, OF MISHAWAKA, INDIANA, ASSIGNOR TO MISHAWAKA RUBBER & WOOLEN MANUFACTURING COMPANY, OF MISHAWAKA, INDIANA, A CORPORATION OF INDIANA.

SHOE.

Application filed March 15, 1924. Serial No. 699,408.

My invention relates to shoes, boots and overshoes or galoshes, all of which are included herein in the term "shoes" and has reference more particularly to the provision 5 in connection with a quick operating non-adjustable fastener of an arrangement whereby the size of the upper portion of the shoe may be varied.

I have shown my invention herein in connection with an overshoe of the type commonly worn by women. As such overshoes are usually made with a high top, it is customary to provide a number of fasteners arranged at intervals along the upper to insure proper closing together of the separable portions of the upper, and these fasteners are made adjustable so that the size of the upper may be varied somewhat to fit the leg, ankle and instep of the wearer. Inasmuch as these 20 fasteners must be separately fastened and unfastened, they are more or less inconvenient, and it is desirable to provide a quick operable fastener which will connect the separable side portions of the upper without the 25 inconvenience of manipulating a number of separate fasteners. However, the quick operating fasteners are not adjustable to permit variation in the size of the upper to fit the leg, ankle and instep of the wearer, and this has been found to be a serious objection 30 to the practical use of such fasteners.

The principal objects of my invention are to provide shoes with a quick operating fastener wherein the size of the upper may be varied to fit the leg, ankle and instep of the wearer; to provide an adjustment in connection with the quick operating fastener which does not interfere with the permanent closing gusset or tongue which is commonly secured to the edges of the separable side portions of the upper; to provide an adjusting arrangement for the upper which may readily include an emergency fastener which permits removal of the shoe in case the quick operating fastener fails to function; and in general, to provide a simple and convenient adjustment in connection with a quick operating fastener, which does not affect the security of or protection afforded by the shoe

and which also serves to enhance the appearance of the shoe. 50

On the drawings:

Fig. 1 is a perspective view of an overshoe embodying my improvements;

Fig. 2 is a similar view, showing the overshoe opened up by releasing the quick operating fasteners; 55

Fig. 3 a similar view, showing the overshoe opened up by releasing the adjustable buckle or snap fasteners; 60

Fig. 4 a transverse sectional view, taken through the upper part of the overshoe;

Fig. 5 an enlarged fragmentary front view of the quick operating fasteners with the front plate of the operating member broken 65 away and other parts in section to show the manner in which the fasteners interengage;

Fig. 6 a sectional view on the line 6—6 of Fig. 5; and

Fig. 7 a sectional view on the line 7—7 of 70 Fig. 5, and showing adjoining portions of the walls of the overshoe.

Referring to the drawings, the reference numeral 1 indicates as a whole an overshoe, the upper part of which is divided down the 75 front into two side portions 2 and 3. A folding gusset or tongue 4, which is sufficiently wide to permit the upper part of the overshoe to be spread apart to any necessary extent, is interposed between the two side portions 2 and 3, and has the side edges secured 80 respectively to the side portions 2 and 3, near the forward edges thereof to close the gap between the side portions 2 and 3, and this gusset or tongue 4 folds back at the sides of 85 the leg as indicated at 5, when the overshoe is fastened in place.

A strip 6 of material, preferably like the rest of the upper, is permanently secured to the overshoe at its lower end as indicated at 90 7, and is provided along the outer side at spaced intervals with fasteners 8 for securing said flap to the side portion 2, and is provided along the other edge with a series of quick operating fastener members 9 which 95 cooperate with a similar series of complementary quick operating fastener members 10 on the forward edge of the side portion 3,

which are adapted to be interlocked or disengaged by means of a slider 11 in its movement from end to end of the series of fasteners 9-10.

5 The fastening device 9-10-11 is of a well-known type, consisting of tapes 12 and 13 which are secured respectively to the forward edges of the strip 6 and side portion 3. The adjacent edges of these tapes are 10 provided with a cord or beading 14 to which the fastener members 9 and 10 are clamped at close intervals so that the fastening members on the one tape are staggered with respect to and fit snugly between the fastener 15 members on the other tape. The fastener members 9 and 10 are alike, and have their outer ends formed with a recess or cavity 17 on the under side and an upwardly projecting lug 16 at the top so arranged that the 20 lugs on each series of fastener members 9 and 10 engage in the recesses or cavities 17 of the other series of fastener members, thereby interlocking the fastener members 9 with the fastener members 10 when these series of 25 fasteners are brought together into an aligning or parallel position. When the tapes 12 and 13 are bent away from one another as shown in the upper portion of Fig. 5, a separation of adjacent members 9 and 10 occurs, 30 which releases the interlocking engagement of the catches 14 and 15 and permits separation or engagement thereof.

For the purpose of operating these catches in the required manner to engage and disengage same, the slider 11 is employed, which comprises opposed plates 20 and 21 which are held together by an integral portion 22 at the top and a spacing rivet 23, and the lateral edges of these plates are bent inwardly 40 as at 24 and 25 around the outer edges of the fasteners 9 and 10. The lower extremities of the inturned portions 24 and 25 are positioned so as to force the fasteners 9 and 10 into the interlocking position, while the upper portions are divergently arranged to form guides for directing the fasteners 9 and 10 inwardly to the interlocking position, or to permit divergence of the series of fasteners 9 and 10 for separating same. The 45 spacing rivet 23 is tapered somewhat along the lower edge to serve as a deflector for directing the two series of fasteners 9 and 10 outwardly, and the top portion 22 of the slider 11 has wings 26 bent down as shown 50 to cooperate with the spacer rivet 26 in directing the fasteners 9 and 10 to and from the interlocking position. With this construction the movement of the slider 11 along the juncture line of the two series of fasteners 9 and 10 serves, as it moves in one direction, to bring these fasteners together and interlock same, and in the other direction to divert and separate same. A plate 15 or other suitable means, is attached to the slider 60 11 for conveniently operating same, and

stops 18 are secured to the upper ends of the tapes 12 and 13 to limit the upward movement of the slider.

The fasteners 8 may be of any desired type, whereby the inner edge of the flap 6 may be 70 adjustably connected to the side portion 2, but are preferably detachable so as to afford an emergency release in the event that the quick operative fastener fails to function 75 properly.

The fasteners shown herein are of a particularly convenient type, comprising a series of snap fastener elements 27 on the side portion 2 of the overshoe, which are adapted to be engaged by complementary snap fastener elements 28 which are adjustably mounted on straps 29 secured at corresponding intervals along the inner edge of the flap 6. The fastener elements 28 in the present form are secured to the under side of plates 30 which are slotted adjacent the ends to provide apertures through which the strap 29 may be inserted, and this strap is inserted through one of these slots, over the top of the plate 30 and down through the other slot as indicated, the edges of the slots nearest the fixed ends 29 being preferably serrated or toothed as indicated at 31, so as to afford a sufficient grip to hold the strap against sliding movement. With this construction the size of the upper part of the overshoe may be readily varied by adjusting the fasteners 28 along the straps 29, so that the overshoe properly fits the leg of the wearer, and it is unnecessary to employ the snap fasteners for applying or removing the overshoe unless the quick operative fastener should fail to work.

It is to be noted that with this construction the gusset or tongue 4 is secured to the side portions 2 and 3 and serves to permanently and separably connect the side portions and close the front of the overshoe when either the quick operating fasteners or the snap fasteners are released, as the flap 6 is merely interposed between the quick operating fasteners and the snap fasteners and covers the forward edge of the side portion 2.

While I have shown and described my invention in a preferred form, I am aware that various changes and modifications may be made without departing from the principles of my invention, the scope of which is to be determined by the appended claims.

I claim as my invention:

1. In a shoe, the combination of an upper having separable side portions one of which is composed of two sections, a quick operating fastener for connecting the two side portions comprising opposed series of interlocking parts adapted to be interlocked and released by the movement of a slider along the juncture line of said parts, and a plurality of spaced independently adjustable means connecting the two sections of the aforesaid side 120 125 130

portion for varying the size of the upper part of the shoe.

2. In a shoe, the combination of an upper having separable side portions one of which is composed of two sections, a quick operating fastener for connecting the two side portions and comprising opposed series of interlocking parts having a slider movable along the juncture line of the parts for interlocking and releasing said parts, and a plurality of detachable fasteners connecting the two sections of the aforesaid side portion and affording an adjustable connection whereby the size of the upper portion of the shoe may be varied.

3. In a shoe, the combination of an upper having separable side portions, a foldable member interposed between and having the lateral edges secured to the separable side portions for closing the gap therebetween and permitting sufficient separation thereof for inserting the foot in the shoe, an upwardly extending strip overlying the front part of one of the side portions of the upper, a quick operating fastener connecting the forward edge of said strip to the forward edge of the other side portion of the upper and adapted to be interlocked and released by a slider which is movable along the juncture line thereof, and a plurality of detachable fasteners arranged at intervals along the rear edge of said strip and connecting the latter to the side portion of the shoe over which said strip is positioned, said fasteners having an adjustable connection with said strip whereby the size of the upper portion of the shoe may be varied.

4. In a shoe, the combination of an upper having separable side portions, one of which is provided with an extension overlying the forward portion thereof and adjustably connected thereto at a distance from the forward edge, a quick operating fastener connecting the forward edge of said extension with the forward edge of the other side portion of the upper and comprising opposed series of interlocking parts, and a slider operable along the juncture line of said parts for interlocking and releasing said parts, and a laterally extensible closing member interposed between and having the lateral edges secured

to the separable side portions of the upper for closing a variable gap therebetween.

5. In a shoe, the combination of an upper having separable side portions, a strip extending upwardly along the upper and overlying the front of one of the side portions, a quick operating fastener connecting the forward edge of the strip to the forward edge of the other side portion and comprising opposed series of interlocking parts and a slider adapted to interlock and release said parts by movement along the juncture line thereof, a plurality of straps arranged at intervals along the rear edge of the strip and having fastener elements adjustably connected thereto, and a plurality of complementary fastener elements arranged at corresponding intervals along the side portion of the upper which is overlaid by said strip and adapted to detachably interlock with the fastener elements on the straps.

6. In a shoe, the combination of an upper having separable quarters, a flap extending along and secured to the edge of one of the quarters by a slider operated separable fastener, said flap being extended over and detachably and adjustably connected to the other quarter at the side of the shoe.

7. In a shoe, the combination of an upper having separable quarters, a flap extending along and secured to the edge of one of the quarters by a slider operated separable fastener, said flap being extended over the other quarter and provided with concealed fastening means carried by said flap and adjustable transversely thereof detachably engaging and covering corresponding fastener means on the latter quarter.

8. A shoe comprising an upper parted at the front to afford separable side portions, a flap extending along one side of and laterally from the line of parting, a separable fastener secured to the edge of one of the side portions of the upper and to the lateral edge of the flap adjacent the line of parting, and spaced means for adjustably connecting the flap to the other side portion of the upper and extending beyond the other lateral edge of the flap and connecting therewith the other side portion of the upper.

GEORGE W. BLAIR.
